UNITED STATES PATENT OFFICE.

JOHN F. SHEAHAN, OF CANTON, ILLINOIS, ASSIGNOR TO INTERNATIONAL HARVESTER COMPANY, A CORPORATION OF NEW JERSEY.

PLOW.

Application filed February 19, 1927. Serial No. 169,428.

The invention relates to improvements in plow bottoms and particularly to means for connecting a sheet metal frog with a detachable share.

5 The principle object of the invention is to substitute a pressed steel frog structure for the cast or malleable frogs heretofore in use and to simplify the structure thru which the share is detachably interfitted with and 10 locked to the frog and other parts of the plow body.

A further object is to provide assembling means comprising a minimum number of 15 loose parts and having its share locking mean so organized as to hold the share in position by means of but one tension element engaging an integral abutment on the frog.

The invention, therefore, resides in the improved features of construction herein- 20 after set forth and particularly defined in the appended claims.

Referring to the drawing,— Figure 1 is a bottom perspective view of 25 a plow embodying the invention; and

Figure 2 is a detail view showing the frog and share separately and as positioned prior to assembly.

For purposes of illustration, the invention is shown in Figure 1 as applied to a walking 30 plow comprising a bottom 10, moldboard 11, share 12, landside 13, cross brace 14 connecting the moldboard and landside, and handles 15 connected to the moldboard and beam, respectively. A heel piece 16 is preferably 35 secured to the end of the landside. With the exception of the frog, these parts are of conventional construction. The moldboard 11 is connected to the frog by one or more bolts 17, and the landside 13 is also rigidly 40 connected to the frog as by bolts 18 and for purposes of this disclosure these parts are regarded as permanently connected. The detachable share 12 is provided with a landside flange or gunnel 19, which forms a continuation of the landside 13 and is formed 45 with the usual cutting edge which joins the moldboard on the line 20 in the usual manner. The frog consists of a sheet metal plate bent to provide angularly related portions 21, 22 engaging the landside and moldboard, respectively, and which extend forwardly beyond the same to form a toe portion 23 similarly engaging the share.

The landside flange of the share is provided with an inwardly projecting stud 24 50

which extends beneath the end of the toe 23 of the frog which is cut away to form a seat 25 which engages the stud 24 when the parts are assembled. The part of the frog engaging the under side of the moldboard and share is formed with free parallel edges 26, 27 connected by a right angular edge 28 forming a beveled shoulder 29 connecting the two parallel edges. At the rear, the edge 26 terminates in an upstanding lug or ear 30 stuck up from the metal of the frog and provided with an aperture or bolt opening 31 for a purpose to be described. The shoulder 29 is so located as to bridge or intersect the junction line between the moldboard and share when the parts are assembled.

It will be noted that the edge 26 of the frog is substantially parallel with the free edge of the moldboard and that the ear 30 is parallel and co-extensive with the shoulder 75 edge 29. The share has on it a stud 32 which is preferably formed with a laterally extending flanged head to provide a hook-like abutment. This stud is so positioned that it will lie in the angle between the edges of 80 the frog and directly opposite the shoulder 29 when the parts are assembled. For connecting the share and frog and drawing up the parts into fixed relation, there is provided a tension bolt 33 provided with a flattened offset head 34 having an opening 85 which is adapted to pass over the head of the stud 32. The head of the bolt bears on the beveled shoulder 29, and its screw-threaded end passes thru the aperture 31 in the ear 90 30. The nut 35 bears against the outer side of the ear and serves to draw up the bolt to lock the share to the other parts of the plow body, the head of the bolt engaging the shoulder 29 to assist this action. Preferably 95 a clip 36 is secured to the under side of the share to overlap the under side of the moldboard and to assist in retaining the share in position. The rear end of the frog may be formed with a raised seat 37 for reception 100 of the plow beam.

It will be clear from the above description that a simple interlocking structure for detachable shares has been devised, characterized by the use of a pressed steel frog so related to the moldboard and share as to bring the locking element in position to apply tension in a direction parallel to the moldboard edge and bringing the share firmly and securely in position against the moldboard,

55 105 110

landside, and frog, and using but one loose element, the bolt 33, in its construction, which bolt is so located as to be conveniently accessible.

5 The above disclosure exemplifies but one preferred form of the invention, which may be varied within the scope of the following claims.

What is claimed as new is:

- 10 1. The combination with a plow body comprising a moldboard, landside, a sheet metal frog permanently connecting said parts and a detachable share interfitting with the moldboard, landside and frog; of means for locking the share in position comprising a stud on the share, an upright ear struck up from the metal of the frog at the moldboard edge thereof, and a locking element connecting said stud and ear.
- 15 2. The combination with a plow body comprising a moldboard, landside, a frog permanently connecting said parts and a detachable share interfitting with the moldboard, landside and frog; of means for locking the share in position comprising a laterally extending shoulder formed on the middle portion of the frog, an integral apertured lug on the frog in alignment with said shoulder, a stud on the share adjacent said shoulder, and a locking bolt received in the apertured lug and having a head engaging the stud.
- 20 3. The combination with a plow body comprising a moldboard, landside, a frog permanently connecting said parts and a detachable share interfitting with the moldboard, landside and frog; of means for locking the share in position comprising a laterally extending shoulder formed on the middle portion of the frog the edge of

the share and moldboard, a stud on the share opposite said edge of the shoulder, an integral lug formed on the frog parallel with said edge of the shoulder, and a fastening bolt connecting the stud and lug and formed with a part bearing on said shoulder.

4. In a plow body assembly, the combination with the moldboard, landside and share, of a sheet metal frog holding said parts in assembled relation and bolted to the moldboard and landside, the portion of said frog engaging the moldboard having a free longitudinal edge terminating at the rear in an upstanding ear struck up from the metal of the frog, and releasable interlocking connections between the frog and share including a stud on the share and a tension bolt connecting the stud with the ear on the frog.

5. In a plow body assembly, the combination with the moldboard, landside and share, of a sheet metal frog holding said parts in assembled relation and bolted to the moldboard and landside, the portion of said frog engaging the under sides of the moldboard and share being formed with parallel free longitudinal edges connected by an angularly related edge forming a shoulder located at the junction line between the share and moldboard, a stud on the share located in the angle between said parallel edges, an integral ear on the frog adjacent its moldboard edge, and a tension bolt extending parallel to the moldboard edge of the frog and connecting the stud and ear.

In testimony whereof I affix my signature.

JOHN F. SHEAHAN.
